ATTY

UNITED STATES PATENT OFFICE.

HERMANN A. KLEMM, OF NEW YORK, N. Y.

TAKE-UP FOR SEWING-MACHINES.

SPECIFICATION forming part of Letters Patent No. 667,712, dated February 12, 1901.

Application filed May 2, 1900. Serial No. 15,186. (No model.)

To all whom it may concern:

Be it known that I, HERMANN A. KLEMM, a citizen of the United States of America, and a resident of New York city, county and State 5 of New York, have invented certain new and useful Improvements in Take-Up Apparatus for Sewing-Machines, of which the following is a specification.

My invention consists of improvements in 10 the construction and arrangements of take-up apparatus for the needle-thread in sewing-machines, as hereinafter described, reference being made to the accompanying drawings, in which—

5 Figure 1 is a side elevation of a sewing machine with part of the front side of the case detached, showing the application of my improved take-up apparatus. Fig. 2 is a side view of the take-up apparatus and part of the 20 needle-bar and its connections with the needle-operating lever, detached and enlarged, with a part of the head of the needle-bar and presser-supporting arm in section. Fig. 3 is a plan view of the take-up apparatus with 25 some parts in section.

A represents the base portion of the machine, which is suitably inclosed. a represents the hollow needle-bar and presser-supporting arm with its front plate removed.

30 c is the needle-bar-working lever. It is pivoted at e and connected at the end of its short arm by rod f with an eccentric (not shown) on the driving-shaft g, as usual. h is the needle-bar. It has a short arm i clamped to 35 it, one extremity of which is coupled by a link j with the end of the long arm of the needle-bar-working lever, and the other end of said arm i works in a slot k of the head l of the supporting-arm a for guiding the needle-bar properly. All these parts, however, 40 are of common form and are not claimed herein.

The take-up apparatus which is the subject 45 of the claims is constructed and arranged as follows: A lever m is pivoted at n to a bracket o, attached to the under side of the top plate of arm a. One arm of said lever reaches forward through a slot p in the head l of said arm a and has an eye q, through which the 50 thread s is strung, and the threaded end of said lever-arm plays up and down between two perforated thread-guides t, through which the thread is also strung, said thread being

led from the tension device and spool through a guide 9, which is adjustable vertically, also 55 through an eye 10 in the upper end of the needle-bar h and through a fixed guide 11. The other rearwardly-extending arm of said take-up lever has a cam-slot u, in which a stud v works, which is carried on one side of 60 a rocking disk w, pivoted at x on a branch y of bracket o, the end of which is attached to a lug z of the lower plate of said supporting-arm a. The rocking disk w has a radial slot 2, in which a stud-pin 3, carried in one side 65 of the lever c, works to cause the stud-pin v to traverse the cam-slot u, and thus operate the take-up lever. The form of the cam-slot and the location of the stud v on the rocking disk are gaged in the proper relations with 70 the movements of the needle-bar for timing the operations of the take-up with the needle, as usual in such cases.

The essential advantage of the apparatus is a contrivance of mechanical parts of simple construction, easy operation, and durability in service. 75

A take-up device for a looper-thread 4 is represented at 5 in connection with a reciprocating looper 6 and a looping-hook 7, used 80 in connection with the needle 8; but these are not claimed and need not be further described.

Any suitable arrangement of thread-guides may be employed, and I do not mean to be 85 limited to the arrangement of guides shown.

What I claim as my invention is—

The combination with the supporting-arm of a sewing-machine the needle-bar-operating lever, and suitable needle-thread guides, of 90 the take-up lever pivoted intermediately of its ends on the supporting-arm with its thread-carrying end in suitable relation with said thread-guides, and having the cam-slot in its rear arm, the rocker-disk also pivoted on the 95 supporting-arm and having the stud-pin engaging the cam-slot of the lever, also having the radial slot, and the stud-pin of the needle-bar-operating lever engaging said radial slot.

Signed at New York city, New York, this 100 30th day of April, 1900.

HERMANN A. KLEMM.
